DESIGN FOR A SHOE

Albert Hurtig, St. Louis, Mo., assignor to The
G. Edwin Smith Shoe Company, Columbus,
Ohio, a corporation of Ohio

Application March 28, 1935, Serial No. 56,103

Term of patent 3½ years

To all whom it may concern:

Be it known that I, Albert Hurtig, a citizen of the United States of America, residing in the city of St. Louis, State of Missouri, have invented a new, original, and ornamental Design for a Shoe, of which the following is a specification, reference being had to the accompanying drawing, forming part thereof, in which:—

Fig. 1 is a side elevation of a shoe, slightly in perspective, showing my new design;

Fig. 2 is a plan view of the shoe.

I claim:

The ornamental design for a shoe, substantially as shown.

Signed at St. Louis, Missouri, this 20th day of March, 1935.

ALBERT HURTIG.
